(57) **CLAIM**

The ornamental design for in-wall coffee maker, as shown and described.

DESCRIPTION

FIG. 1 is a front perspective view of an in-wall coffee maker showing my new design;

FIG. 2 is a right side elevation view of the coffee maker of FIG. 1, the left side elevation being substantially a mirror image thereof; and,

FIG. 3 is a top plan view of the coffee maker of FIG. 1. The broken lines in the drawings are for illustrative purposes only and form no part of the claimed design.
